ELECTRICAL SOCKET CONNECTORS

Sidney Geoffrey Young, London, England

Application January 19, 1954, Serial No. 405,016

5 Claims. (Cl. 339—256)

This invention relates to electrical socket connectors of the type adapted to receive and grip resiliently a pin of an electric plug or a like member inserted therein. Although the pin may be of any cross-section, the invention is particularly applicable to a socket connector designed to receive a pin of either round or rectangular cross-section.

The objects of the invention comprise the provision of an improved pin-gripping effect and of a construction of socket especially suited to simple and economical manufacture and assembly.

Embodiments of the invention are illustrated diagrammatically on an enlarged scale and by way of example only in the annexed drawing, in which

Figure 1 is a side view of a socket connector according to the invention prior to insertion thereof of a pin of an electric plug or the like;

Figure 2 is a similar but fragmentary view of the same connector with such a pin partly inserted;

Figure 3 is a similar but fragmentary view of the same connector with the pin pushed home;

Figure 4 is a plan view of Figure 1;

Figure 5 is an end view of Figure 1;

Figure 6 is a section on the lines VI—VI of Figure 3; and

Figure 7 is a view similar to Figure 5 of a modification.

The connector shown in Figs. 1 to 6 consists of a stamped out or otherwise formed piece of stiff sheet metal having suitable electrically conducting properties, such piece being bent at one end into a rounded U-shaped portion 1 including opposed, substantially parallel side limbs (as best seen in Figure 5 or 6) and at the other end 2 into a suitable shape for connection to a cable or other terminal. This latter end 2 of the connector is shown of round cross-section in the drawing, but it may be modified as required for any particular application, the novel aspects of the invention not being concerned with this end of the connector.

In each of the side limbs 7 of the U-shaped portion 1 of the connector, there is cut a slot 3 of double V shape. In these two slots 3 are supported a number of resilient plates 4 which extend across the open top of the U-shaped portion 1. In the drawing, four such plates are shown. This number may however vary widely. Even one such plate may suffice, but usually it is preferred to employ at least two plates. By so doing it thus becomes possible to make the lowermost plate of a material particularly suitable for establishing contact with the pin, e. g. Phosphor-bronze, and to make the remaining plate or plates of a material such as spring steel having the desired mechanical properties. When only one plate is used it will preferably be of a composite structure or compromise material having as far as possible good mechanical and electrical properties. In addition, the provision of a plurality of plates has the advantage of permitting the use of thin section springs for each indi-

2

vidual plate, while at the same time providing a combination the total effect of which is to give adequate pressure against the inserted pin, combined with flexibility.

5 In the case where the lowermost, contact-making plate 4 is of a comparatively highly conducting material, it is preferable that such plate should be slightly longer than the remaining plates (this being shown in the drawing at 5 on Figure 4), in order that the pin should always 10 make contact first and break contact last with this plate.

The plates 4 may be held against lateral movement out of the slots 3 by means of a casing (not shown) surrounding the connector, or in any other convenient manner.

The action on insertion of a pin 6 is shown clearly in Figure 2. Firstly, the plates are tilted by virtue of the shape of the slots 3, and finally, as the pin 6 is pushed home, they are returned to a horizontal position and centrally bowed, as appears from Figure 6. This latter figure shows how the lower contact-making plate is pressed against the lower surfaces 8 of one end of the slots 3 by reason of such bowing of the plates.

The form that the slots 3 take may vary widely. For example, instead of the closed construction provided in the illustrated embodiment, the slots may be open at the end of the connector at which the pin 6 is introduced. They could then be limited in their forward movement on withdrawal of the pin by suitable surfaces on the casing. Furthermore, with either an open or a closed slot construction, one or more of the plates may be made of such a length relatively to the slots, as to extend beyond the end of the portion 1 of the connector. As a further alternative form of construction, the slots may be rectangular instead of the double V shape shown. 35 When this latter construction is employed, and if desired when the double V-shaped slots are employed, the lower end edge of the U-shaped portion 1 may be bent downwardly slightly to form a lip and thus facilitate entry of the pin 6.

40 As already explained, the embodiment described is only given by way of example and numerous modifications are possible within the scope of the invention. For example, if a pin of cross-section other than round is to be accommodated, then the U-section of the socket will be correspondingly modified. In particular, for use with a pin of rectangular cross-section, the base of the U may be flat instead of arcuate, or the U-section may be pointed at the bottom to receive a square pin arranged on one edge.

45 Finally, the base of the U-shaped portion 1 of the form of the invention shown in Figs. 1 through 6 may be removed altogether and replaced by a second set of plates 4' which extend through slots adjacent the lower edge of side plates 7', such second set of plates 4' consisting either of a single plate or of a number of plates similarly constructed and disposed as are the plates 4 above described. This latter type of construction is shown in Fig. 7, from which it will be seen that the connector also includes a pair of opposed, substantially parallel plates which constitute the straight sides 7' of the connector, such straight sides each having adjacent their upper edge a slot similar to those shown at 3 in Figs. 1 to 3, and such upper slots, in the preferred form of the present invention, bearing four resilient plates 4.

50 This invention is particularly noteworthy in providing a construction of extreme simplicity of manufacture and assembly, due to the simple shapes employed and the small number of parts required.

70 I claim:

1. An electric socket connector of the type adapted to receive and grip resiliently a pin of an electric plug insert-

ed therein, such connector comprising an elongated hollow socket member of generally U-shaped internal cross-section, the side limbs of said socket connector each having an axially-extending slot therein adjacent the upper edge thereof and the resilient plate extending across from a slot in one side limb of the socket member to the slot in the opposite side limb of such member.

2. A socket connector as claimed in claim 1, wherein a plurality of superposed plates is employed extending between the slots in the side limbs of the socket member, and wherein the plate which is adjacent the interior of the said hollow socket member is made of a material chosen primarily for its electrically conducting property and at least one of the remaining plates is of a material chosen primarily for its mechanical property.

3. A socket connector as claimed in claim 1, wherein the underside edges of the said slots are shaped to provide a fulcrum about which the plate or plates may be pivoted by pressure from an inserted plug pin from a position in which they extend back from the mouth of the socket member generally parallel to the lower edge thereof, to a position in which they extend back from the mouth of the socket member while being inclined towards such lower edge.

4. An electric socket connector of the type adapted to receive and grip resiliently a pin of an electric plug inserted therein, such connector comprising an elongated hol-

low socket member including spaced, substantially parallel side members and means extending across the lower part of the socket member to form the bottom thereof, said side members each having an axially-extending slot therein adjacent the upper edge thereof, and a resilient member extending across the top of said socket member from the slot in one side member to the slot in the other side member, said resilient member constituting the top of said socket member and resiliently engaging the pin inserted in said socket member.

5. A socket connector as claimed in claim 4, wherein said resilient member comprises a plurality of superimposed plates, and wherein the plate which is adjacent the interior of the said hollow socket member is made of a material chosen primarily for its electrically conducting property and at least one of the remaining plates is of a material chosen primarily for its mechanical property.
